UNITED STATES PATENT OFFICE

CHARLES P. TOLMAN, OF NEW YORK, N. Y., ASSIGNOR OF ONE-HALF TO PETER C. McNULTY, OF MILWAUKEE, WISCONSIN

METHOD OF DETERMINING STREAM LINE CONTOURS

No Drawing.

Application filed November 18, 1929. Serial No. 408,175.

The invention relates to a method for accurately determining the proper stream line contours for aeroplanes and their appurtenances, such as wings, rudder, running gear, ailerons, nacelles, etc.

Heretofore it has been the practice to arrive at the contour of aeroplanes, their wings and other parts which are exposed to the elements by a method of successive appropriations whereby starting with an assumed design or with a design embodying certain assumptions improvement has gradually been developed by comparative tests and by mathematics based upon data obtained from such designs, such former methods being in effect a "cut any try" process. The object of the present invention is to quickly and readily design parts of an aeroplane subjected to stream line flow which accurately conform to the natural laws of stream line flow past these parts so that following the present method the parts of the aeroplane may be readily designed to have the proper stream line contour.

The invention further consists in the method or steps of the method hereinafter described and more particularly defined by claims at the conclusion hereof.

The process, in brief, consists in subjecting an aeroplane, either of full size or of model size, to the action of flow or air in a suitable wind tunnel and causing a deposition of some suitable substance upon the part going under test so that the final contour of the surface past which the air is flowing will be built up to the proper contour to conform to actual conditions when the aeroplane is subjected to movement through the air.

The preferred way of carrying out this method is to utilize a substance which may be readily carried along in an air stream and converted from a liquid into a solid state for deposition on the surfaces to be treated. More specifically, in this instance the process consists in putting a full size aeroplane or a scale model of the type of aeroplane to be built into a suitable wind tunnel and either through natural or artificial means providing a temperature of the atmosphere in the tunnel which is below freezing and then subjecting

the aeroplane or its counter model to a flow of air at suitable velocity and injecting into the air a spray of water or steam which is carried into the stream of freezing air and brought into impinging contact with the plane in order to freeze thereon, particularly in the dead corners and other regions where there is an eddying effect—it being particularly noted that the greater deposition of frozen particles will occur at the dead corners and in the regions where there is an eddying effect—so that these deficiencies of the design may be corrected.

By this action the shape will be gradually built up, always approaching true stream line contours. When the point has been reached which on observation shows no substantial change in contour, the change being only a general building up over the whole area, the air blast and water spray is shut off and the contour of the surface is ready for recording by direct measurement. This point might be determined, when the work is being done in a regular wind tunnel, by noting the load on the means by which the head resistance of the aeroplane is measured. When this resistance has reached a minimum and begins to show an increase the process should be stopped. Measurements can be made in any well known manner, as, for example, by measurements referred to known coordinates by bending thin strips of plastic material, such as lead, about the surfaces and subsequently scribing the curves so reproduced; by means of molds made of plaster of Paris or other suitable material; or by such other method or methods as may prove most convenient or suitable to obtain the measurements of the contour produced in accordance with this method.

It is desirable to produce in the wind tunnel those atmospheric conditions under which sleet forms on an aeroplane in actual service.

One specific manner of carrying out the invention has been described above for the sake of simplicity, but there are obviously many alternatives, as, for example, instead of using freezing atmosphere and water in this process, air at ordinary temperatures or hot air could be used and any combination

with suitable adhesive material and finely divided particles could be caused to adhere to the structure, as, for example, any suitable glue could be sprayed into the air together with a suitable finely divided solid, such as wood flour, sawdust, kieselguhr, and the like, and deposited upon the plane to build up the desired contour in the same manner that the freezing moisture produced this result.

It is also clearly obvious that the aeroplane could be sprayed from time to time with adhesive material, such as glue, and subsequently blasted with air carrying finely divided solids to produce the same result.

Obviously the general type of aeroplane should be embodied in the model which is subjected to the process, but in some instances it might be desirable to skeletonize all or certain parts of the structure.

While the invention has been described with particular reference to aeroplanes and is of extreme importance with reference thereto, it is within the scope of the same to utilize the process hereinbefore described in connection with high speed transportation vehicles of known forms and types and in connection with the determining of the proper stream line contour of other surfaces subjected to a flow of air or other fluids so that in its broad aspect the invention is not to be limited solely to its use in connection with aeroplanes.

I desire it to be understood that this invention is not to be limited to any particular material for carrying the process into effect except insofar as such limitations are contained in the claims.

What I claim as my invention is:

1. The method of determining the stream line contour of aeroplane surfaces or of the parts or auxiliaries thereof which are subjected to air flow which consists in subjecting the aeroplane or said surfaces to a flow of air past the surfaces, introducing a substance into said flow of air for deposition on said surfaces in accordance with the natural laws governing stream line flow over said surfaces bringing about a condition producing a deposition of said substance on said surfaces, and continuing said deposition until the optimum shape is obtained as indicated by air resistance measurements made simultaneously with the subjection of said surface to the air flow and deposition.

2. The method of determining the proper stream line contour for surfaces of an aeroplane and its auxiliaries which consists in placing an aeroplane or a suitable replica thereof in a wind tunnel, passing air through this wind tunnel at freezing temperature, spraying a fluid capable of freezing into said air and depositing the sprayed fluid upon the surfaces being treated in accordance with the natural flow of air past said surfaces and al-

lowing the same to congeal thereon until no further improvement in the shape of the surface takes place, as indicated by a measured increase in resistance of the surface to the flow of the air stream.

In testimony whereof, I affix my signature.

CHARLES P. TOLMAN.
